THERMOELECTRIC DOOR OPERATING
MECHANISM

Vernon Durbin, Waban, and Charles T. Button,
Needham, Mass., assignors to National Pneu-
matic Co., Inc., Boston, Mass., a corporation
of Delaware

Application November 13, 1950, Serial No. 195,332

1 Claim. (Cl. 268—66)

1

This invention relates to door operating mechanism, and particularly to the opening and closing of doors by power; the application of the power being under the control of electrical connections responsive automatically to changes in the rate of heat transfer at a control point in the vicinity of the door or doors to be operated.

In places where rooms adjoin and communication there-between is by way of doors, also in the case of garage doors and doors in factories, stores, warehouses, etc., it is often desirable to have the door open automatically when a person or object approaches and to close immediately after the person or object has passed through the doorway. An arrangement of this sort is particularly useful for operation of doors which connect a dining room to the kitchen of a restaurant or hotel and which are continually being opened by persons whose hands may not be free to push the door.

Electrical control devices, as heretofore known, have commonly required the erection of stanchions (as in photoelectric systems), or metallic guide-rails (as in electrostatic capacitance systems), which stanchions or guide-rails would operate to set off the initiating impulse, for operation of the doors only after entry of a person (or vehicle) into the space directly between said stanchions or guide-rails. The system herein disclosed differs from these prior systems in that the operation is initiated by the mere approach of a person (or vehicle) from any angle or direction, and without the need of erecting either stanchion, guide-rails, or other auxiliary mechanism in the approach path.

An object of the invention, therefore, is to provide a system of control of door operation wherein the mere approach of a person, or object, sets off an electrical initiating impulse; the impulse emanating from a single control element mounted unobtrusively in a wall or ceiling of the building, out of the actual path of approach, but within the range of energy radiated by the approaching person, or object.

A second object of the invention is to provide, in a system of the character indicated, a control element whose electrical characteristics vary sharply in response to a relatively slight change in the rate of heat applied thereto.

A third object is to provide, in a system having

2

such a control element, means for sharply varying the rate of application of heat to such element in response to the approach of a person, or object, and with such rapidity as to cause the operation of the door to occur well in advance of actual arrival of the person, or object, at the door-way itself.

In the drawings:

Fig. 1 is a diagrammatic illustration of the system;

Fig. 2 is a schematic showing of electrical parts and connections that are preferable to those illustrated in Fig. 1 where conditions are such to permit; and Fig. 3 shows a further modification.

15 The arrangement is shown as applied to door operation, but it is, of course, apparent to those skilled in the art that the system is adapted for controlling and operating any form of passage-controlling device. There is shown in the drawing a building wall 5 in which a door 6 is mounted, along with a vertical shaft 7 which may rotate about a fixed vertical axis. Supported over the door is a pneumatic motor 8 which is connected to the door shaft by pivotally interconnected levers. A valve 9 is electro-magnetically actuated to direct compressed air into and out of the motor 8, in alternate stages. This manner of operating doors and the interconnection of the parts is so very well known in so many forms that it is believed that the diagrammatic illustration is sufficient. It may also be noted at this point, as will be apparent to those skilled in the art, that although a pneumatic motor is disclosed, any other form of power device may be 20 equally well controlled and be employed for operating the door.

It is also here noted that the electromagnetic valve 9 and its association with a pneumatic motor is very well known in the art. The 25 terminals of the solenoid winding of the electromagnetic valve are connected to the terminals of the secondary winding of a transformer 11 whose primary winding is under the control of a thermionic device 10 for amplifying energy supplied to the device now to be described.

40 Mounted in the wall 4, adjacent the door, is an energy collecting device having three major components, namely, a reflector 20, a semi-conductive resistance element 21 of the thermally 45 sensitive or "thermistor" class, and a window 22

of a material, such as rock salt, through which infra-red as well as all other light rays will readily pass. The terminals of the thermistor (which may correspond in principle to the element shown at 4 in the drawings of Kock Patent No. 2,522,521) connect with points 50 and 51, respectively, of a Wheatstone bridge whose adjacent arm is formed by a second (non-exposed) thermistor 21a. Across the central points 51, 53 of the bridge is a transformer 12, whose secondary winding is in the control circuit of an electronic amplifier 10 supplying a transformer 11, which in turn energizes the electro-magnetic portion 9 of the door operating valve, heretofore described.

Under favorable conditions it will be found possible to obtain adequate power for operation of the electromagnetic portion of the valve independently of any auxiliary amplifying agent such as the tube 10 of Fig. 1. In such cases it is preferable to substitute the electrical arrangement indicated in Fig. 2, wherein reference numeral 31 designates a relay contact element adapted to move into bridging relationship to a pair of associated contact elements, to deliver operating current from source 32 to the valve operating electromagnet 9, whenever the thermistor 21 (corresponding to the thermistor 21 of Fig. 1) undergoes a sufficiently rapid heat change to render the circuit of the relay winding 33 effective to energize the relay and thus close the circuit to valve magnet 9, at the point 31. For this duty there may be employed, as the magnetic relay 33, an extremely sensitive type of relay, as for example the type known in the trade as a "Sensitrol" relay. Also, if desired, the radiant energy collector 22 may be placed in the direct path of heat rays rising from a heat source specially provided below the floor line of the building. Such a heat source is shown in Fig. 3 as a glow grid 36 adapted to receive energizing current from a source 37, under the control of a switch 38, which may be of the manual or automatic (thermostatic) type. A protective grating 39 (with shielded louvres) would preferably be placed over the glow element 36, with its upper surface flush with the upper surface of the floor.

The thermistor circuit, in either the Fig. 1, Fig. 2, or Fig. 3 embodiment, is of such stability that when there is no person or object in the area of approach to the door, there is no flow of operating current to the winding of the electromagnetic valve 9. However, as soon as a person or object moves toward the door the resistance of the thermistor is sharply changed, causing a potential change at transformer 12 whereby the grid of tube 10 no longer acts to block the flow of electrons to the plate and the device is set in operation. The result is that a current flows in the plate circuit of the tube, and this includes the transformer 11 and (indirectly) the electro-magnetic valve 9. The valve 9 therefore operates to apply compressed air to the engine 8 in a manner to open the door. By the time the person has passed through the open door-way the resistance of the thermistor circuit shifts back to normal and energy flow in the tube 10 ceases. Thereupon the magnet valve returns to normal position, re-directing the supply of fluid pressure so that the engine closes the door. It may be noted here that the engine illustrated is of the differential type wherein fluid pressure is always present in the smaller cylinder and the engine is moved back and forth by supplying compressed air to and exhausting it from the larger cylinder. This type of operation is well known in

the art. Obviously, any other type of engine may be employed, in which case the magnet valve may be modified as required. Alternatively, in lieu of a fluid pressure engine there may be substituted an electric motor for operating the door, in which event the valve 9 will be replaced by an electric current controller.

While Fig. 2 shows heat conducting rods 23 interconnecting the heat ray receiver 22 with the thermistor 21 it is to be understood that such rods constitute merely one of the methods of delivering the operating energy to the thermistor. Alternatively, the energy delivered to the thermistor by direct radiation can be sufficient to produce the intended operation, particularly if the material comprising the energy collector 22 is the rock salt window illustrated in Fig. 1, through which the infra-red as well as the visible light rays may pass without impedance. With a heat receiver so constructed the energy radiations of infra-red wave lengths will be sufficient to produce virtually instantaneous response on the part of the thermistor 21 independently of any supplementary assistance, much as the heat conducting rods 23 of Fig. 2.

By using the Wheatstone bridge arrangements of Fig. 1, with two thermistors 21 and 21a in adjacent arms of the bridge, opposite fixed resistors R, and R₂ of known values, and with only thermistor 21 exposed to the energy ray striking collector 22 (the thermistor 21a being shielded therefrom) there is produced a control circuit that is promptly responsive, self-compensating in action, and adapted to prolong the energy flow in tube 10 for the complete duration of each successively created condition of unbalance in the bridge itself, and to cut off such energy flow promptly upon restoration of bridge balance.

What we claim is:

In the combination of a door movably mounted in a wall, a power device operatively connected to said door for opening it, a control for said power device, and an electric circuit connected to said control for actuating the latter; the improvement which consists of a device located in one of said door or said wall adjacent said door and exposed to the space in the vicinity of said door through which a person or object must pass to reach said door, said device detecting and being sensitive to radiations in the infra-red range, said device including a temperature-sensitive resistor the resistance of which is sensibly altered by the detection by said device of infra-red radiations emanating from a person or object entering said space in the vicinity of said door, a second similar temperature-sensitive resistor shielded from the effects of infra-red radiation in said space in the vicinity of said door and in circuit with said first resistor so as to balance out ambient effects, a source of electric energy in circuit with said resistors, and an operative connection between said resistor circuit and said control-actuating circuit, the former controlling the latter, and hence said power device, in accordance with the detection or non-detection by said device of radiations in the infra-red range emanating from a person or object entering said space in the vicinity of said door, whereby the approach of said person or said object to said door will cause said door to open.

VERNON DURBIN.
